UNITED STATES PATENT OFFICE.

JOHN VERMEULEN, OF NEW YORK, N. Y.

KNIFE-POLISHER.

SPECIFICATION forming part of Letters Patent No. 434,365, dated August 12, 1890.

Application filed January 14, 1890. Serial No. 336,878. (No model.)

To all whom it may concern:

Be it known that I, JOHN VERMEULEN, a subject of the King of Belgium, residing in the city, county, and State of New York, have 5 invented a new and Improved Knife-Polisher, of which the following is a full, clear, and exact description.

The invention consists of certain parts and details and combinations of the same, as will 10 be hereinafter more fully described, and then pointed out in the claims.

Reference is to be had to the accompanying drawings, forming a part of this specification, in which similar letters of reference indicate 15 corresponding parts in all the figures.

Figure 1 is a side elevation of the improvement. Fig. 2 is a plan view of the same. Fig. 3 is a transverse section of the same on the line $\alpha\alpha$ of Fig. 1. Fig. 4 is a similar view of 20 the same on the line $\gamma\gamma$ of Fig. 1. Fig. 5 is a face view of a sharpening-roller of modified form. Fig. 6 is a side elevation of the same, and Fig. 7 is a plan view of the spring-plate for holding the stationary strap in place. 25

The improved knife-polisher is provided with a suitably-constructed bed-plate A, from one end of which, at the under side, extends an L-shaped arm B, in which screws a screw C, for securely fastening the bed-plate A to a 30 table or bench. On the front end of the bed-plate A is mounted a knife-polishing device D, provided with a fixed polishing-strap E and a yieldingly-mounted strap F, of which the latter is located above the former, and between which the knife to be polished is placed, 35 as hereinafter more fully described.

The straps E and F are preferably made of leather; but other suitable material may be employed. The strap E is stretched transversely over part of the bed-plate A, and has its ends extending downward and over the downwardly and inwardly inclined lugs or flanges A', formed on the under side of the bed-plate A. The ends of the strap E are securely held in place by a spring-plate G pressing the ends of the strap against the inclined lugs A', as is plainly shown in Fig. 3. When the strap E is worn out, it can be easily and conveniently replaced by prying the spring- 45 plate G from under the bed-plate A, then removing the worn-out strap, replacing it by a

new one, and then again inserting the spring-plate G, as above described. The other strap F is passed under a plate H, provided at its sides with upwardly and inwardly bent lugs or flanges H', over which pass the ends of the strap F, which are held in place at the inside of the said lugs or flanges by a spring-plate I, similar to the spring-plate G, previously mentioned. At the inner end of the plate H are formed upwardly-extending lugs J, each provided with a vertical slot J', through which pass the ends of a pin K, held in the lugs A² erected on the bed-plate A, as is shown in Fig. 2. The vertical slots J' in the lugs J permit the plate H 60 to rise parallel with the bed-plate A, and also to swing upward when a wedge-shaped knife is inserted between the two straps E and F, the pin K thus being the fulcrum.

On the pin K, between the lugs A², is coiled 70 a spring L, having its middle part extended upward to engage a screw N, screwing in a lug O', formed on an offset O, held on the rear of the bed-plate A and forming part of the knife-sharpening device. The ends of the 75 spring L extend at about right angles to the upwardly-bent or middle part of the said spring and press on the top of the plate H, so as to hold the strap F of the latter against the strap E or against the knife when inserted. 80

In the middle of the plate H is formed a hopper P, which opens through an aperture F' in the strap F upon the stationary strap E. This hopper is adapted to receive the 85 polishing material, which can pass from the hopper through the opening F' between the two straps E and F, or upon the knife when inserted between the two straps.

The offset O, previously mentioned, and forming part of the knife-sharpening device, 90 is provided with a vertically-extending slot O², into the lower part of which pass the rims of the two sharpening-rollers R and R', secured on shafts Q and Q', mounted in the offset O, parallel with the sides of the slot O². 95 Each of the rollers R and R' has V-shaped annular ridges R² on its periphery. The outer sharp edges of the V-shaped ridges nearly touch the center of the slot O², as is plainly shown in Fig. 1, so that when a knife is inserted in the slot O² and pressed down on the rollers, and drawn inward or outward, its 100

knife-edge comes in contact with the sharp edges of the ridges of the two rollers R and R', and is thereby sharpened.

The shafts Q and Q' are each provided on one outer end with a toothed wheel S or S', respectively, each having V-shaped teeth adapted to be engaged by a square plate T, held between the two wheels and adapted to engage oppositely-arranged teeth, so as to prevent the said wheels from turning to hold the rollers R and R' in place. The plate T is secured at one end on a transversely-extending shaft U, arranged to slide in suitable bearings in the offset O, and provided at its outer end with a head U', on which presses one end of a spring V, held in a suitable recess O³ of the offset O. The spring V has the tendency to press the head U' outward, thus holding the plate T in contact with the front face of the offset O, at the same time engaging the said plate with the toothed wheels S and S'. When the rollers R and R' have become worn by use at the point which extends into the slot O², then the operator presses on the head U' of the shaft U, so as to shift the shaft U inward, thereby disengaging the plate T from the notched wheels S and S'. The operator can then turn the notched wheels the distance of one or more teeth, so that new points of the ridges R² of the rollers R' and R come in the slot O².

The device is used as follows: The bed-plate A is secured in a suitable manner to a table, bench, or bracket, and when the operator now desires to polish a knife he first fills the hopper P with a polishing material and then inserts the knife between the straps E and F in such a manner that the knife-edge extends toward the pin K. The spring L then presses the strap F firmly in contact with the top of the knife, while the bottom of the knife rests on the lower stationary strap E. As the knife is usually wedge-shaped in cross-section, the upper strap F assumes an inclined position, turning on the pin K, as previously described. The tension with which the spring L presses on the plate H can be regulated by adjusting the screw N, so that the spring L presses with more or less force on the knife to be polished. The operator then moves the knife-blade transversely between the two straps E and F, so that it is polished by the said straps and the polishing material passing to the said straps and the knife, as is previously described. When the knife has been polished or cleaned and the operator desires to sharpen it, he places the knife-blade in a vertical position with the knife-edge downward and inserts it in the slot Q² until the knife-edge rests on the V-shaped ridges R² of the rollers R and R'. The operator then draws the knife-blade transversely several times, pressing down on it so as to hold the knife-edge firmly in contact with the V-shaped ridges of the rollers R and R' while drawing the knife forward and backward. The knife is thus sharpened.

The sharpening-rollers R and R' may each be made of solid steel or of a series of washers placed on the respective shaft Q or Q', as shown in Figs. 5 and 6. In order to hold the washers on the shaft, the latter is provided with a flattened side, and a corresponding aperture is formed in each washer.

It will be seen that the device is very simple in construction, can be cheaply manufactured, and will form an indispensable household article.

The knife-sharpening devices are not claimed herein, but will form the subject of a separate application.

Having thus fully described my invention, I claim, as new and desire to secure by Letters Patent—

1. A knife-polisher consisting in the stationary plate A, having depending parallel ribs or flanges A' A' along its side edges, a strap E, passed over the plate and around the said ribs or flanges, a spring clamping-plate extending from rib to rib and clamping the ends of the strip against said ribs, and an upper spring-pressed plate having parallel upwardly-projecting ribs or flanges H' along its side edges, a strap F, passed along the lower face of said plate and having its ends folded over said ribs or flanges, and a clamping-plate extending from one rib H' to the other and clamping said overturned ends thereto, substantially as set forth.

2. The combination, with the lower plate and its polishing-strap, of a vertically-movable spring-pressed plate having upwardly-projecting parallel ribs or flanges H' along its side edges and a hopper P on top of and opening through the plate between said flanges, the strap extending along the lower face of the plate and having its ends folded over said ribs, and the spring-plate I, extending from rib to rib and having an opening between its marginal edges to pass the said hopper, substantially as set forth.

3. The combination, with the plate A, having vertical lugs A² at one end of the polishing-strap passed over said plate, of the plate H, provided with lugs J parallel with the lugs A² and having vertical stops J', a pin passed through the lugs A² into said slots, a polishing-strap secured to plate H, a spring L, passed around said pin, bearing at its ends on top of plate H and having a loop above the plate, and a set-screw passed through the loop for adjusting the spring, substantially as set forth.

4. A polisher consisting in the bed-plate A, having an attaching clamp, parallel depending ribs A' A' along its side edges, lugs A², lug O' above and between said lugs A², the strap passed over said plate and having its ends folded over said ribs, the spring-plate G, sprung between said folded ends and clamping them against said ribs, the plate H, having a central hopper opening through it on its upper side, lugs at its inner end having vertical slots, and ribs H along its side edges,

the strap F, the ends of which fold over the ribs H, the spring-plate I, sprung between said folded ends and clamping them to the ribs, the pin K, the spring L, passed around 5 said pin, with its ends resting on plate H at opposite sides of the hopper and looped above the pin, and the set-screw N, mounted on the lug O' and engaging said loop, substantially as set forth.

JOHN VERMEULEN.
